US00D559764S

(12) **United States Design Patent** (10) **Patent No.:** **US D559,764 S**
(45) **Date of Patent:** **** Jan. 15, 2008**

(54) **HELICOPTER**

(75) Inventor: **Chi Pok Billy Wai**, Quarry Bay (HK)

(73) Assignee: **Silverlit Toys Manufactory, Ltd.**,
Hong Kong (HK)

(**) Term: **14 Years**

(21) Appl. No.: **29/283,033**

(22) Filed: **Aug. 3, 2007**

Related U.S. Application Data

(63) Continuation-in-part of application No. 11/627,919, filed on Jan. 26, 2007, which is a continuation-in-part of application No. 11/465,781, filed on Aug. 18, 2006, which is a continuation-in-part of application No. 11/462,177, filed on Aug. 3, 2006, application No. 29/283,033, which is a continuation-in-part of application No. 29/275,322, filed on Dec. 20, 2006, now Pat. No. Des. 546,269, and a continuation-in-part of application No. 29/275,323, filed on Dec. 20, 2006, now Pat. No. Des. 544,825, and a continuation-in-part of application No. 29/275,324, filed on Dec. 20, 2006, now Pat. No. Des. 545,755, and a continuation-in-part of application No. 29/277,652, filed on Mar. 5, 2007, now Pat. No. Des. 552,531, and a continuation-in-part of application No. 29/280,187, filed on May 18, 2007, now Pat. No. Des. 554,040.
